Chesler Granger 510 9875X
The schedule referred to in this Letter Patent and making
part of the same containing a description in the words of
the said Chesler Granger himself of his improvement in
the Cooking Stone.

To all to whom these presents shall come
Be it known that I Chesler Granger of Pittsfield in
the County of Rutland and State of Vermont have in-
vented a new and useful improvement in the Cooking
Stone and that the following is a full and exact descrip-
tion of the construction and operation of the said Cooking
Stone and the improvement thereof, as invented and impro-
ved by me. The Cooking Stone for which the improve-
ment herein is a device, is usually made with firebox
or consisting of four cast iron plates set upon a hearth or
bottom. The front part of the hearth or bottom may be made
from any fire brick of any character and on a level
width of it is an oven placed on the rear part of the before
mentioned bottom. Still back of this oven there is a sliding
flue for the smoke to pass off and the smoke and heat
pass through and over the oven, into this flue, there is a large circular plate placed over the firebox or
oven. This plate is stationary. The front part of this
plate an open space is cut out nearly as large as large
as the fire chamber, and placed directly over it. The
rear part of this plate and the open space is cut out, through
which the smoke passes into the sliding flue. In the centre
of this circular plate, is a socket designed for the centre pin of
the top plate hereafter described, on the outside of this circular
plate are placed four friction rollers, on which the top
plate, hereafter described, rests and revolves. This circular
plate is covered by another circular plate in diameter a
little larger than the lower circular plate, this upper

circular plate is called the cap or top of the flange. This cap is placed centrally over the lower circular plate before description. On the lower circular plate is a groove on the outer edge and on the upper circular plate or top, is a flange or lip which fits into the groove on the lower circular plate. The cap or top is placed from one to two inches above the lower circular plate. That part of the cap which extends over the lower circular plate rests upon a roller upon the before-mentioned friction rollers. The flange or lip of the top or cap is made of a width proportioned to the distance of the upper and lower circular plates apart and extends down just far enough to accurately fit into the groove on the lower circular plate. The cap or top is pierced with boiler holes in such number and size as convenience and a due regard to the size of the boiler may require. These holes are designed for boiler or other parts of boiler to rest in workings and they are each surrounded with a raised edge or rim just sufficient to prevent the boiler or other materials and steam, from going in its place. The surface of this top plate on the inside of these boiler holes is raised from two to six inches above the surface of the same top plate on the out-side of the boiler holes. On the inside of these boiler holes the rim is just sufficient in width as before mentioned to keep the boiler which may be placed, in or on such boiler hole steadily. On the out-side of the boiler holes the rim slopes down from two to six inches till it comes to the level of the out-side or lower part of the cap. Between the boiler holes also the upper or raised surface of the top or cap which is contained on the outside of the boiler holes slopes down in a curve until it comes to a level with the out-side or lower part of the cap plate. The edge or rim around the boiler holes may be kept on as before described or may be left entirely off, so that the interior

surface of the top plate between the boiler holes would be exactly on a level with the boiler holes) as convenience may dictate. The drawing of the top plate shows nothing accompanies this description. It refers to as making a part of the same. On the inside of this plate is placed a hollow cast iron box of the form here to accompany it, and marked A. This box is fastened to the inner side of the cap by a bolt and some iron rivets and cleats. On the lower side of this box is a center piece or pivot designed to fit into the socket before mentioned, in the lower circular plate. The sides of this box are arched in such a manner as to fit the dimensions of the boiler which is designed to come next to them and each side is curved so as to be exactly fitted to the boiler intended to be inserted. This box may be made of whatever weight is judged most expedient. The center piece or pivot above mentioned may be placed upon the lower side of this box. This last method is taken when it is desired to extend outside of the boiler just the center of the cap. The cap or top plate covers this box and as before described on the space between the boiler holes, may be exactly on the level with the boiler holes or the boiler holes may be surrounded with a narrow edge or rim, to keep the boiler guides or other tools used, from and steady in their places. On the outside of the boiler holes the top plate slopes down something more than the width of this box and the boiler holes also the top plate slopes down in a curve the same width as before described. The object of this center box is to raise the inner part of the top or cap within the boiler holes, nearly or quite to the level of the boiler holes thereby, shortening the great convenience and expediency in cleaning that part of the top plate when it is on a level with the part of the top plate which is outside of the boiler holes. The object in

lended to effect by the lip, occurring from the lower part of the anterior bay, is that the lip by altering the form and dimensions of the anterior bay a larger body may be cut out by bending beyond the centre of the lip. The upper part of this bay and lip may be used in other rotary stones as well as in one of the forms above described. The improvement of which I claim the invention and for which I wish letters patent of the United States consists in the anterior bay used with or without the lip as before described. The writer of this of Stone Successor set myself
